CARRIER ROD STOP CONTROL ARM FOR
FULL FASHIONED KNITTING MACHINESMelchior Zwicky, Berkshire Heights, Pa., assignor
to Textile Machine Works, Wyomissing, Pa., a
corporation of PennsylvaniaApplication September 14, 1931
Serial No. 562,705

9 Claims. (Cl. 66—129)

This invention relates to stop control means for the thread feeding guide rods of full fashioned knitting machines, and more specifically to a rod releasing stop arm of the type set forth in Patent 5 No. 1,079,915 of November 25, 1913, employed, in connection with usual end stops, to control additionally carrier rod stopping or rod releasing as required for particular thread feeding movements; the object of the present improvements 10 being to adapt said arm for a variety of control movements by providing the same with movable rod-contacting stops variably positioned for engagement with selected carrier rods.

The nature of the improvements and the varied 15 stop control movements secured thereby will be more fully described in connection with the accompanying drawing, and the novel features of the invention specifically set forth in the appended claims.

20 Referring to the drawing,—

Fig. 1 shows in rear elevation a partial view at one end of a full fashioned knitting machine embodying the present improvements.

Fig. 2 is an enlarged view of the rod releasing 25 stop arm shown in Fig. 1, certain associated parts being indicated in dotted lines.

Fig. 3 is a cross sectional view on the line 3—3 of Fig. 2.

Fig. 1 indicates a usual end spindle 1, having a 30 traversed stop nut 2 thereon carrying end stops 3 for the thread carrier rods 4, all as heretofore and operating in known manner. The rod releasing arm is indicated at 5 with an extension 6 engaging the slur cock bar 7.

This arm 5, as described in the aforesaid patent, 35 transversely overlies the carrier rods 4, and is pivotally mounted on a fixed shaft 8 along which it slides as moved by nut 2, or a separate nut, on spindle 1, so as to maintain a fixed relation to 40 end stop 3, and it acts in known manner to stop a carrier rod after a limited travel, as for a selvage edge reenforcement, or to detain a rod and timely release the same, as for proper lead of a carrier rod in plating, determined by suitably 45 placed dogs 4^a on the carrier rods, and a cam 9 on bar 7 acting on arm extension 6.

The lower edge of arm 5 heretofore has been 50 straight to engage, when in lowered position, any rod carried dog, or said edge has been recessed to clear dogs on certain rods and act only on dogs on other rods, limiting the control of said arm and necessitating substitution of another arm for change of operation. The present improvements are intended to adapt an arm of this 55 type for varied control operation on the several

rods, as will now be described in connection with the specific construction shown in the drawing.

The arm 5 normally rests on spaced supports of nut 2, and its lower edge 10, between the latter, 60 is cut away to freely pass any rod having a stop dog 4^a except as the latter contacts with a movable rod stop 15 mounted on said arm. Such movable stop 15 is indicated as pivotally secured to the side of arm 5 by a pivot bolt 16, with an 65 upwardly projecting operating handle 15^a and its lower end radially swingable across the carrier rods and divided to form two extensions 17 and 18 overlying spaced carrier rods, adjustable headed bolts 19 and 20 in said extensions forming the 70 stops or dog-engaging contacts and providing for accurate setting. The stop 15 may be swung on its pivot bolt 16, by means of the handle 15^a so as to position either extension 17 or 18 to overlie the intermediate carrier rod. Stop 15 is 75 shown with a spring projected locking bolt 30 engaged with any of the recesses 21 in the side face of arm 5, said recesses being spaced to correspond with carrier rod spacings, and bolt 30 is retracted from such engagement by a lever 23, 80 pivotally mounted at 24 on stop 15, and having a forked lower end engaging a pin 25 in the projecting stem of said bolt. The lever 23 is positioned close to handle 17, so as to facilitate retraction of the bolt 30 preliminary to swinging 85 stop 15 on its pivot 16.

The particular stop 15 shown and above described is adapted to selectively control several carrier rods as determined by its setting, and such control may be a positive stop against further 90 rod movement, or may be temporary and released by action of bar 7 on extension 6 to lift arm 5, such releasing timing the delayed movement of the engaged carrier rod relative to another rod or rods.

Control of additional carrier rods may be readily provided for by the addition of another pivotal stop 15 on the same or on the opposite side of arm 5, and two such equipped arms 5 may be arranged in spaced relation on a spindle nut for special control movements, providing for a 95 convenient and simply effected variety of carrier rod movements.

From the foregoing description it is believed 105 the nature of the improvements and their manner of operation will be readily understood, and it is obvious that the specific construction set forth may be readily modified within the scope of the invention defined in the following claims.

What I claim is:

1. In a knitting machine having reciprocable thread carrier rods each provided with stop members, an arm extending transversely of said rods adapted to carry stop devices engageable by said stop members to control the movements of said rods, and means for moving said arm from rod controlling position; the combination therewith of a stop device mounted on said arm for movement relatively to said carrier rods into position for selectively engaging the stop members of determined rods.
2. In a knitting machine having reciprocable thread carrier rods each provided with stop members, an arm extending transversely of said rods adapted to carry stop devices engageable by said stop members to control the movements of said rods, and means for moving said arm from rod controlling position; the combination therewith of a stop device on said arm mounted for movement thereon into a number of positions for selectively engaging the stop member of any one of a plurality of said rods.
3. In a knitting machine having reciprocable thread carrier rods, an arm extending transversely of said rods adapted to carry stop devices engageable by said rods to control the movements of said rods, and means for moving said arm from rod controlling position; the combination therewith of a stop device pivotally mounted on said arm to swing radially across said carrier rods for selectively engaging determined rods.
4. In a knitting machine having reciprocable thread carrier rods, an arm extending transversely of said rods adapted to carry stop devices engageable by said rods to control the movements of said rods, and means for moving said arm from rod controlling position; the combination therewith of a stop device on said arm having a plurality of rod contacting stops radially swingable across said rods into and out of engaging relation with determined rods.
5. In a knitting machine having reciprocable thread carrier rods, an arm extending transversely of said rods adaptable to carry stop devices engageable by said rods to control the movements of said rods, and means for moving said arm from rod controlling position; the combination therewith of a stop device on said arm having a plurality of rod contacting stops each selectively engageable with a plurality of rods.
6. In a knitting machine having reciprocable thread carrier rods, an arm extending transversely of said rods adapted to carry stop devices engageable by said rods to control the movements of said rods, and means for moving said arm from rod controlling position; the combination therewith of a stop device on said arm hav-
- ing a plurality of rod contacting stops radially swingable across said rods for simultaneously engaging a plurality of rods.
7. In a knitting machine having reciprocable thread carrier rods, an arm extending transversely of said rods adapted to carry stop devices engageable by said rods to control the movements of said rods, and means for moving said arm from rod controlling position; the combination therewith of a stop device mounted on said arm for movement relatively to said carrier rods into position for selectively engaging the stop members of determined rods; locking means for holding said stop device in radially adjusted position for cooperation with a determined rod; and a lever for releasing said locking means and shifting said stop device to another radial position for cooperation with another rod.
8. In a knitting machine having reciprocable thread carrier rods each provided with stop members, an arm extending transversely of said rods and carrying stop devices engageable by said stop members on the thread carrier rods to limit the movements of said rods, and means for moving said arm from rod controlling position; the combination therewith of a stop device pivotally mounted on said arm for radial movement relative to said carrier rods into position for selectively engaging the stop members of determined rods; spring actuated locking means for holding said stop device in radially adjusted position for cooperation with the stop of a determined rod, and a lever for releasing said locking means and shifting said adjustable stop device to another radial position for cooperation with the stop of another thread carrier rod.
9. In a knitting machine having reciprocable thread carrier rods, stop members thereon, an arm extending transversely of said rods carrying stop devices engageable by the said stop members on the thread carrier rods to limit the movement thereof, and means for moving said arm from rod controlling position; the combination therewith of a stop device mounted on said arm for movement relative to said carrier rods into different positions for selectively engaging the stop members of determined rods, said arm having openings therein; a spring actuated plunger carried by said stop device and adapted to register with and enter said openings to maintain the stop device in adjusted position for cooperation with the stop of a determined rod, and a lever operable upon the spring actuated plunger to withdraw it from an opening to release the pivoted stop device and permit the said device to be moved to another position for cooperation with the stop of another thread carrier rod.
